UNITED STATES PATENT OFFICE.

GEORGE M. YARNELL, OF SENECAVILLE, OHIO.

PUMP ATTACHMENT.

SPECIFICATION forming part of Letters Patent No. 489,403, dated January 3, 1893.

Application filed July 9, 1892. Serial No. 489,472. (No model.)

To all whom it may concern:

Be it known that I, GEORGE M. YARNELL, a citizen of the United States, residing at Sene-
5 caville, in the county of Guernsey and State
of Ohio, have invented certain new and useful
Improvements in Waste-Spout Attachments
for Pumps; and I do declare the following to
be a full, clear, and exact description of the
invention, such as will enable others skilled
10 in the art to which it appertains to make and
use the same, reference being had to the accom-
panying drawings, and to the letters of
reference marked thereon, which form a part
of this specification.

15 This invention relates to certain new and
useful improvements in attachments for
pumps, and it has for its object to provide a
simple and inexpensive device which may be
readily attached to any of the various styles
20 of pumps, and which will serve to catch the
drippings from the pump spout and convey
the same back into the well, thus effectually
preventing the annoyance occasioned by the
water running over the platform or accumu-
25 lating in pools upon the surface, as is fre-
quently the case, especially where the pump
is in frequent use.

My device is adapted to be hinged to the
pump stock in such a manner as to permit of
30 its being thrown automatically into operative
position by gravity, when the vessel filled has
been removed from beneath the pump spout,
and to be readily moved back out of the way,
when the vessel is placed beneath the spout.

35 To these ends and to such others as the in-
vention may pertain, the same consists in the
novel construction, and in the peculiar ar-
rangement, combination and adaptation of
40 parts, all as more fully hereinafter described,
shown in the accompanying drawings, and
then specifically defined in the appended
claim.

The invention is clearly illustrated in the
accompanying drawings, which, with the let-
45 ters of reference marked thereon form a part
of this specification, and in which drawings;—

Figure 1 is a perspective view of a pump
provided with my improved attachment. Fig.
2 is a similar view, in which the attachment
50 is shown as thrown back by the pail placed
beneath the pump spout.

Reference now being had to the details of
the drawings by letter, A designates a pump
of ordinary construction, provided with the

usual operating handle B, and spout C. The 55
front face of the pump stock is provided with
a groove D, which extends from a point
slightly above the platform of the well down-
ward, and pivoted or hinged to the face of the
stock, at the upper end of this groove, is the 60
lower end of the spout or trough F. This
trough is preferably wider at its upper than
at its lower end, and at its upper end is pro-
vided with a heavy metallic wire or rod G,
the ends of which extend for a short distance 65
beyond the side edges of the trough, and are
formed with loops G' within which loops are
secured the ends of the chains H, the oppo-
site ends of which chains are attached to the
body of the pump; the chains being of such 70
length as to permit the trough G to fall out-
ward for a sufficient distance to catch the
drippings from the pump spout.

It will be readily seen that by this con-
struction, the spout or trough F will normally 75
occupy a position beneath the pump spout,
and will serve to catch and convey drippings
therefrom back into the well, and it will also
be seen that it will offer no resistance to the
pail or other vessel which may be placed be- 80
neath the spout.

While I have shown a particular form of
spout or trough, and prefer this construction,
still, it is at once evident that both the form
of the trough, and the mode of attachment of 85
the same to the pump, may be varied, with-
out departing from the spirit of my invention;
which contemplates the use of a hinged waste
spout beneath the spout of the pump.

Having thus described my invention, what 90
I claim to be new and desire to secure by Let-
ters Patent, is;—

The combination with a pump and its spout,
of a waste trough hinged at one end to the
pump, the throw of the upper end being lim- 95
ited by chain fastenings to the pump and
adapted to be automatically thrown into and
out of operative position by the placing or re-
moving of a pail or other vessel beneath the
pump-spout, and serving to convey the drip- 100
pings from the spout back into the well, sub-
stantially as shown and described.

In testimony whereof I affix my signature in
presence of two witnesses.

GEORGE M. YARNELL.
